BRUSH SPRING ASSEMBLY

William T. Taber, Bloomfield, N. J., assignor to
 Bendix Aviation Corporation, Teterboro, N. J.,
 a corporation of Delaware

Application January 24, 1944, Serial No. 519,581

2 Claims. (Cl. 171—324)

1

This invention relates to spring assemblies commonly employed in generators and similar electrical equipment, for the purpose of urging brushes into engagement with a commutator or slip ring.

It is usual to employ a spiral spring for this purpose. Ordinarily such a spring is anchored at its inner end, and after being tensioned its outer end engages the brush to urge the latter as above indicated.

With the known arrangements certain difficulties have developed which are overcome by the present invention. When a spiral spring of the type commonly used is tensioned, and with its inner end fixed, there is a distortion in the shape of the spring which results in an elongation in one direction. Thus, the turns of the spring are moved out of their normal position with a greater degree of space on one side and a corresponding lessening of the spacing on the opposite side. In the latter instance the turns of the spring often rub together to create friction which is, of course, a factor which it is desirable to avoid.

If the spring is unconfined there is danger of these distorted turns contacting the frame of the electrical apparatus with a resulting short-circuit. If the spring is confined, the distorted turns will engage the casing and create additional friction.

An object of the invention is the provision of a spring assembly of the type noted in which a spiral spring is mounted within a casing with its inner end anchored to a member that is adapted to be rotated to partially tension the spring.

Under a condition of partial tensioning, the outer turn of the spring might engage the casing wall, but when the tensioning is complete, as by moving the outer end into brush engaging position, all turns of the spring are substantially free from each other and the outer wall and a condition of symmetry obtains. Thus, the spring is adapted to function with substantially no frictional resistance and definite assurance is had that the brush will be properly urged into commutator engaging position at all times.

Various other more detailed objects and advantages of the invention will in part become apparent and in part be hereinafter stated as the description of the invention proceeds.

For a full and more complete understanding of the invention, reference may be had to the following description and drawing, wherein:

Fig. 1 is a top plan view of a brush spring

2

assembly made in accordance with the precepts of this invention;

Fig. 2 is an end view mostly in elevation, but partly in section, showing the manner in which the brushes are affected by the spring assembly;

Fig. 3 is a view developing the various elements of the assembly in exploded relation;

Fig. 4 is a detailed section taken about on the plane represented by the line 4—4 of Fig. 3;

Fig. 5 is a section through the assembly taken on a plane normal to the shaft on which the springs are mounted; and

Fig. 6 is a diagrammatic showing bringing out the relative position of the turns of the spring.

Referring now to the drawing wherein like reference characters denote corresponding parts, and first more particularly to Figs. 1, 2 and 3, a supporting bracket is therein depicted and referred to in its entirety by the reference character B. The bracket B comprises a flange 10 which may be affixed to the casing or supporting structure of the particular piece of equipment in which the assembly is being installed.

Thus, the flange 10 might be affixed to the casing of a generator through the medium of fastening elements which pass through the openings shown at 11. If desired, a piece of insulation, such as shown at 12 in Fig. 2, might be interposed between the flange 10 and the casing.

Integrally joined to the flange 10 is a main frame 13 having a rectangularly shaped opening 14 through which the extremities of the springs to be later described are adapted to pass. This frame 13 may carry end flanges 15 and a downwardly depending front flange 16 to which is secured a bracket member 17. A shaft 18 is carried by this bracket member 17 in spaced relation to the remainder of the plate 13 and associated structure, as is clearly brought out in Fig. 3.

It will be noted that shaft 18 is formed at each end with an opening 19. One pair of springs is adapted to be mounted on one end of the shaft 18 and a similar pair on the other end. In the illustrated embodiment of the invention the assembly is shown as including four springs which are identified as 20, 21, 22 and 23. The springs 20 and 21 are assembled as a pair on one end of shaft 18, and the springs 22 and 23 as a pair on the other end.

Inasmuch as these pairs of springs are substantially duplicates and each spring being similar to every other spring, only one of them is here described for the purpose of this specification.

55

Disposed about the shaft 18 for rotary adjustment thereon is a sleeve 24 formed with a longitudinal kerf 25. This sleeve may be provided with a suitable wrench engaging means, such as the hex-head indicated at 26. The outer end of the sleeve 24 is formed with several sets of diametrically opposed openings 27, any one set of which is adapted to align with the opening 19, and in this position receive a cotter pin 28.

A spring proper is designated 29. This spring is of the flat spiral type well known in this art and has its inner end bent over into a flange that is received in the kerf 25. The outer end of the spring is bent into the U-shaped formation shown at 31, and this bend receives an actuating member 32 of similar shape which has a foot 33 that engages a brush such as depicted at 34. The brush 34 in turn engages the commutator indicated at 35.

A curved casing or shield is represented at 36 and may be carried by a flat wall or disc-like member 37 that is formed integral with the member 32 and which has a central opening receiving the shaft 18.

In operation, prior to positioning of the member 32 over the brush 34, the spring 29 is first partially tensioned by rotating the inner sleeve 24 a required distance. After the desired degree of tension is established, the cotter pin 28 is positioned in aligned openings 27 and 19 to maintain this relation.

In this condition the outer turn of the spring 29 will probably engage the casing 36. However, when the member 32 is positioned over the brush 34, the spring is tensioned from its outer end and this tensioning frees the outer turn of the spring from the casing 36. Thus, when the spring 29 is in effective brush urging position all turns of the spring are substantially free from each other and the outer casing.

While only one embodiment of the invention is hereinbefore set forth, it is to be clearly understood that the invention is not to be limited to the exact construction illustrated and described, because various modifications of these details may be provided in putting the invention into practice within the purview of the appended claims.

What is claimed is:

1. In a brush holder, the combination of a frame adapted to hold a brush relative to a commutator and having an exterior projection transverse to the commutator axis, a shaft element including an inner end supported by said projection and extending along said axis and having a pin opening adjacent to its outer free end, a sleeve adapted to be fitted over said shaft element from its free end having a plurality of outer end apertures adapted for selective register with said opening for holding by the pin, said sleeve having means next inwardly therealong from said apertures providing for turning the sleeve relative to said shaft element and a kerf extending from adjacent to said turning means toward the inner end of the sleeve, a member at one side of said projection having a plate-like portion through which the shaft element extends, said member including a portion of

substantially Z-shape, one arm of which is adapted to engage said brush, a spiral spring having an inner end in said kerf and an outer end hooked over an intermediate bend of said Z-shape, a disc surrounding said shaft element, and a spring cover portion carried by said disc closed at one end thereby and open at the other end of the cover portion, said cover portion being operative before the spring is operatively loaded to slightly compress outer turns only of the completely relaxed spring, and said sleeve being operative to load the spring from its inner end to reduce tension on said outer turns before the inner turns tighten on each other for maintaining all of the turns in radially spaced relation to each other, said outer turn being in radially spaced relation to said cover portion when operatively related to the brush.

2. In a brush holder, the combination of a frame adapted to hold a brush therein relative to a commutator, a shaft element fixed at its inner end to said frame and having a free outer end and including holding means intermediate said ends, a sleeve adapted to be fitted over said shaft element from its free end and having means adapted for cooperation with said holding means for selectively positioning the sleeve in fixed relation thereto in any of a plurality of positions of the sleeve about said shaft element, a member through which said shaft element extends having an arm adapted to engage said brush, a spiral spring fixed at its inner end to said sleeve and having an outer end biasing said arm toward said brush, a disc-like member surrounding said shaft element, and a spring cover portion carried by said disc, said cover portion being operative before the spring is operatively loaded to slightly compress outer turns only of the completely relaxed spring, and said sleeve being operative to load the spring from its inner end to reduce tension on said outer turns before the inner turns tighten on each other for maintaining all of the turns in radially spaced relation to each other, said outer turn being in radially spaced relation to said cover portion when operatively related to the brush.
